UNITED STATES PATENT OFFICE.

LEONARD J. MARKS, OF SAN FRANCISCO, CALIFORNIA.

MIXING AND COMBINING DEVICE FOR GAS-ENGINES.

No. 819,239.

Specification of Letters Patent.

Patented May 1, 1906.

Application filed May 20, 1905. Serial No. 261,347.

To all whom it may concern:

Be it known that I, LEONARD J. MARKS, a citizen of the United States of America, residing at San Francisco, county of San Francisco, and State of California, have invented certain new and useful Improvements in Mixing and Combining Devices for Gas-Engines; and I hereby declare the following to be a full, clear, and exact description of the same, reference being had to the accompanying drawings, forming a part of this specification.

This invention relates to certain improved devices for modifying, mixing, and combining the charges of fuel-gas supplied to hydrocarbon motive engines, especially those in which the fuel-gas is provided by volatilizing crude mineral oils by heat.

My improvements consist in a structure, technically called a "mixing and combining" valve, placed between the volatilizing or vaporizing apparatus and the engine to be supplied, its functions being to admit air, water, to mix and cool the fuel-gas, also to supply some volatile hydrocarbon that can be employed to start the engine independently and in advance of using the oil fuel.

The objects of my invention are to regulate the amount of air supplied to and mixed with the fuel-gas, to control the temperature of the same, and to provide a separate supply of fuel-gas to be employed in starting, thereby improving the efficiency and convenience of operating hydrocarbon-oil engines. To these ends I provide devices as shown in the drawings herewith.

Figure I is an elevation of the various parts connected, showing their arrangement; Fig. II, an enlarged vertical section through the mixing and regulating devices that form the subject of my invention.

In operating motive engines impelled by gaseous or explosive fuel derived from crude mineral oil the latter is volatilized by heat, usually by the hot waste gas from the engine conducted to and around a chamber or vessel commonly called a "vaporizer." The vapor or gas after being combined with air is then conducted to the motive cylinder and is consumed in charges in the usual manner of engines of this kind. The hot vapor or gas thus produced, if not reduced in temperature before entering the motive cylinder, is unduly hot, expanded in volume, dry and less effective than if saturated to some extent

with moisture, also is liable to produce premature ignition. Moreover, when the mineral oil is volatilized by heat derived from the motive cylinder an auxiliary supply of gaseous fuel has to be provided to start and heat the engine. For these several functions I provide a unitary device. (Illustrated in section by Fig. II of the drawings and herein-after described.)

Referring to the drawings and at first to Fig. I, 1 represents the cylinder of a gas motive engine, 2 the volatilizing or vaporizing chamber, and 3 a pipe through which the hot spent gases are conducted from the engine 1 to the chamber 2.

A discharge-pipe 43 conducts away the waste gases after they have passed the chamber or vessel 2. At 5 is a tank and connecting-pipe for crude mineral oil.

7 is a tank for gasoline or other volatile hydrocarbon fluid easily carbureted or evaporated, and 8 a common valve or cock to close the pipe 9, which conducts the gaseous fuel from the chamber 2 to the motive cylinder 1.

10 is my improved mixing and combining device.

12 is a pipe to conduct the volatile fluid from the tank 7, and 13 a pipe conveying water from the water-space around the cylinder 1 to the regulating-valve 10.

Referring to the regulating device 10, (shown enlarged in Fig. II,) this has several functions, as before stated. It admits and regulates the amount of air to be incorporated with the fuel-gas supplied from the chamber 2, admits water to cool the mixture of fuel-gas and air, and admits when required a volatile hydrocarbon to supply the motive engine until the latter becomes heated and the volatilizing-chamber 2 begins to act. The mixing and combining device 10 is made with an integral body 14, adapted to fit upon and open into the supply-pipe 9, as shown in Fig. I.

15 is the valve that seats upward, as shown in Fig. II, and slides on a stem 17 by means of a tubular extension 18. This extension 18 fits loosely around the stem 17 at the top and is guided at the bottom by a head or enlargement 19 of the stem that also acts as a pneumatic cushion when the valve 15 is closed suddenly. A helical spring 20 bears against the head 19 of the stem 17 and upward against the valve 15 to sustain its weight and offer a

moderate resistance to its opening movement. The extension 18 of the valve 15 is closed at the bottom by screw-plug 22, and the head 19 of the stem 17 has a slot at 23 for use when it is inserted. The stem 17 passes loosely through the distance-collar 31 and is screw-threaded in the seat 24. The latter can be made integral with the main shell 14 or be inserted.

25 25 is a revoluble cap that fits loosely over a nipple 27 of the main body 14, the two being pierced with registering passages 28, that admit an amount of air regulated by the position of the cap 25. A screw 29 is provided 15 to hold the cap 25 in a fixed position when that is required, and the edge 30 is preferably milled to afford a hold for convenient turning. Around the interior of the nipple 27 is placed a fine screen 32 to prevent the entry of any 20 foreign substance with the air. The cap 25 is held down elastically by the hand-nut 33 and a coil-spring 34. This nut 33 when screwed down bears upon a distance-collar 31, jamming and locking the stem 17, a serrated or 25 milled cap 35 on the latter serving to turn and adjust it and the range of the valve 15 from the exterior when in use. Water is admitted through an aperture 37, opening into the seat of the valve 15, a pipe 13 connecting 30 to the cooling water-spaces around the motive cylinder 1. A similar aperture 38 opens into the seat of the valve 15 for injecting a volatile hydrocarbon, such as gasoline, from the tank 7 through the pipe 12. The stem 17 35 has a small hole drilled through its center, connecting with the hole 39 in the head or piston 19 to oil and air the same and maintain a free movement thereof.

In operating and when the engine 1 is to 40 be started the cock 8 is closed and the cock 40 is opened and volatile fluid is admitted through the aperture 38, the valve 15 being pressed down for that purpose. The cap 25 is turned to admit air to the chamber 42 and 45 to the supply-pipe 9, from where it is drawn into the cylinder 1 and ignited. As soon as the engine has been in operation long enough to heat the chamber 2 by reason of the hot waste gases passing through the pipe 3 the 50 resulting vapor or gas flows through the pipe 9, the cock 8 is opened and the one 40 is closed, and the engine begins to operate by the fuel-gas from the volatilizing-chamber 2. When the hot vapor reaches the mixing- 55 valve 10, it is carbureted and partially cooled by the admission of air through the passages 28 and the valve 15. Water is admitted through the cock 42 and aperture 37 to further cool the fuel-gas, and the engine goes on with

its normal charges, the valve 15 opening by 60 suction at each working stroke.

Having thus explained the objects and nature of my invention and the manner of its operation, what I claim as new, and desire to secure by Letters Patent, is—

65

1. In an oil-consuming gas-engine, a volatilizing-chamber, a cylinder, a mixing device interposed between said volatilizing-chamber and the engine-cylinder, said device having an automatically-opening and closing air-valve, an inlet for water controlled thereby, and variably-registering air-apertures for admitting air to said valve in regulated quantity, substantially as specified.

70

2. In an oil-consuming gas-engine, a volatilizing-chamber, a cylinder, a mixing device interposed between said volatilizing-chamber and the cylinder, said device having adjustable means for admitting air in regulated quantities, an inlet for volatile hydrocarbon, 80 to mingle with the admitted air and temporarily supply fuel-gas to the engine in starting, a tank for the volatile hydrocarbon, conducting-pipes from said tank to the mixing device, and means to regulate the amount of 85 volatile fluid supplied, substantially as specified.

75

3. In an oil-consuming gas-engine, a volatilizing-chamber, a cylinder, a mixing device interposed between said volatilizing-chamber 90 and the cylinder, said device having adjustable means for admitting air in regulated quantities, an inlet-way for liquid fuel, an inlet-way for water, means for supplying said fuel and water in regulated quantities, and 95 an automatically opening and closing valve to admit and mix said fluids, substantially as specified.

80

4. In an oil-consuming gas-engine, a volatilizing-chamber, a cylinder, a mixing device 100 interposed between said volatilizing-chamber and the cylinder, said device having adjustable means for admitting air in regulated quantities, adjustable means for supplying liquid fuel and for supplying water thereto in 105 regulated quantities, and an automatically opening and closing valve for admitting and mixing said fluids, said valve being mounted on and guided by a central adjustable stem, accessible from the exterior, substantially as 110 specified.

105

In testimony whereof I have signed my name to this specification in the presence of two subscribing witnesses.
